MACHINE FOR MAKING WIRED BOX PARTS

Alfred L. Rosenmund, Rockaway, N. J., assignor
to Stapling Machines Co., a corporation of
Delaware

Application April 3, 1937, Serial No. 134,789

38 Claims. (Cl. 140—93)

This invention relates to machines for making wired boxes and box parts and particularly to machines for forming and perpetuating U-shaped bights on the ends of wires secured to box parts.

5 It is an object of the invention to provide certain improvements in the type of machine disclosed in my Patent No. 1,933,031 of October 31, 1933, whereby the wired box parts to be operated upon may be automatically fed into and through the machine.

It is a further object to provide an automatic feed for a machine of the type referred to which is controlled by the box parts in their movement to and through the machine.

15 It is a further object of the invention to provide a machine of the type referred to with an automatic control to correlate the operation of the machine with the operation of a box blank machine which staples the binding wire to the box parts.

20 It is a further object of the invention to provide a machine of the type referred to with an automatic feed and a control therefor of such character that a succession of wired box parts leaving a box blank machine will be automatically fed into and through the bight-forming machine.

Other objects will be in part obvious and in part pointed out hereinafter.

30 In the drawings:

Figure 1 is a perspective view of one product of the machine, namely, a wired box blank.

Fig. 2 is a perspective view of another product of the machine, namely, a wired crate blank.

35 Fig. 3 is a perspective view of still another product of the machine, namely, a wired box end.

Fig. 4 is a top plan view of a machine embodying the invention and the delivery end of a box blank machine showing the relationship between the two.

40 Fig. 5 is an enlarged side elevation of the same showing in full lines the position of the control arm when the automatic feed of the bight-forming machine is thrown out of operation and in dotted lines the position of the control arm when the automatic feed of the bight-forming machine is thrown into operation.

Fig. 6 is an end elevation of the bight-forming machine seen from the line 6—6 in Fig. 5.

45 Fig. 7 is an enlarged top plan view of the bight-forming machine with certain parts omitted for clearness of illustration.

Fig. 8 is an enlarged sectional view taken on the line 8—8 of Fig. 6 with certain parts omitted 50 for clearness of illustration and showing the posi-

tion of the parts during operation of the automatic feed.

Fig. 9 is a sectional view similar to Fig. 8 but showing the position of the parts after the automatic feed has been stopped and the bight-forming operation is about to begin.

Fig. 10 is an enlarged plan view of a portion of the bight-forming machine, i. e., the right hand portion in Fig. 7, and shows the position of the parts when the automatic feed is in operation.

Fig. 11 is a side elevation of the same but showing the position of the parts after the automatic feed has been interrupted and the bight-forming mechanism is in operation, certain parts being omitted for clearness of illustration.

Fig. 12 is a side elevation of the other side of the machine.

Fig. 13 is a side elevation of a portion of the machine and showing the release mechanism 20 which automatically starts a bight-forming operation when the feed of the box parts is discontinued.

Fig. 14 is a side elevation of a portion of the machine showing the position of the trigger which 25 controls a bight-forming operation after such an operation has been completed and the box parts are again moving through the machine.

In Fig. 1 is shown one illustrative product of the machine, namely, a wired box blank consisting of four sections of cleats A and side material B connected together in foldable relationship by wires C which extend across and are stapled to the several sections. Each end of each wire C is bent to form a U-shaped bight D, the two bights thus formed being adapted to interengage with each other to close the box when the several sections of the box blank are folded into box form.

In Fig. 2 is shown a crate blank. This blank is similar to that shown in Fig. 1 except that 40 the side material B of the several sections consists of spaced slats.

In Fig. 3 is shown a box end consisting of a sheet B of veneer, resawed lumber or fibreboard, and wires C stapled thereto and provided at their 45 ends with bights D.

In the manufacture of the products shown in Figs. 1, 2 and 3, the wires C are stapled to the box parts in what is commonly known as a box blank machine. A typical box blank machine is 50 shown in U. S. Patent No. 1,738,806 of December 10, 1929, reference to which is hereby made for a detailed description of such a machine.

In the box blank machine the box parts, i. e., the cleats A and the side material B in the case 55

of the blanks shown in Figs. 1 and 2, are positioned on endless conveyor chains and fed beneath staple forming and driving mechanism which staples the binding wires C to the side 5 material and the cleats A. When box ends such as the end shown in Fig. 3 are being made, a succession of sheets B are positioned on endless conveyor chains and fed beneath the staple forming and driving mechanism which staples the wires 10 C thereto.

In the box blank machine such as that disclosed in said U. S. Patent No. 1,738,806 the conveyor chains are advanced continuously at substantially a uniform speed and the staple forming and driving mechanism is constructed and 15 arranged to operate upon the moving box parts.

In placing the box parts on the endless conveyors of the box blank machine adequate spaces are left between units of work, i. e., box blanks 20 or box ends as the case may be, to provide sufficient lengths of wire between each unit to be severed and formed into bights to provide the bights D as shown in Figs. 1 to 3. Thus a succession of wire-connected box blanks or box ends 25 are delivered continuously from the delivery end of the box blank machine with appropriate lengths of wire therebetween to permit severing the wires and forming and perpetuating a bight on each severed end.

Heretofore the wire-connected box blanks emerging from the box blank machine were manually fed into a bight-forming machine of the type shown in said Patent No. 1,933,031. When in correct position to be operated upon in the 30 bight-forming machine, the machine was manually thrown into operation to sever the wires, form prongs on the severed ends, swing the prongs over onto their respective box parts to form bights and drive the prongs through the box parts to perpetuate the bights. After this operation the bight-forming operation automatically stopped and the finished box blank was manually pulled through and removed from the bight-forming machine. This manual feeding of the 35 box blanks to the bight-forming machine and the manual removal of the finished blanks required two attendants for the bight-forming machine.

The present invention is intended to eliminate 40 the necessity for these two attendants by providing an automatic feed for the box blanks to, through and out of the bight-forming machine.

Because the wired box blanks emerge from the illustrative box blank machine continuously 45 and at substantially a uniform speed, and because the bight-forming mechanism of the illustrative bight-forming machine does not operate upon moving work, the present invention includes an automatic control for the automatic 50 feed of the work and an automatic control for the operation of the bight-forming mechanism, both controls being operated in accordance with the relationship of the box parts to the bight-forming machine and mechanism, all of which 55 will now be described.

Referring to Figs. 4 and 5, the box blank machine which staples the binding wires to the box parts is generally indicated by the reference numeral 1, and the bight-forming machine which 60 severs the wires between box parts and forms bights on the severed wire ends is indicated generally by the reference numeral 2.

After the box parts have been wired in the box blank machine they are discharged from that 65 machine by the continuously moving conveyor chains

3. In the absence of mechanism to feed the wired box parts through the bight-forming machine they would of course fall to the ground. Mechanism is provided in the bight-forming machine to pull the wired box parts up onto a curved 5 guide 4 and onto a table T mounted to reciprocate vertically in the bight-forming machine at the proper time, as described in said Patent No. 1,933,031 to present the wires to the operation of the bight-forming and perpetuating mechanism. 10

The mechanism for pulling the wired box parts into and through the bight-forming machine consists of a pair of moving belts 5 which engage the sides of the wired box parts and feed them 15 through the bight-forming machine.

As the work-feeding means of the illustrative box blank machine continuously delivers a succession of wire-connected box parts and as the illustrative bight-forming mechanism operates only when the box parts are at rest, it is necessary to interrupt the movement of the feed belts 20 5 at intervals to permit the bight-forming mechanism to operate, and it is also necessary to so regulate the intermittent feed of the belts 5 with the continuous feed of the conveyor chains 3 of 25 the box blank machine that the bight-forming machine will handle the output of the box blank machine without interrupting the operation of the latter. This is accomplished by running the belts 5 of the bight-forming machine at a higher 30 rate of speed than that at which the chains 3 of the box blank machine are moved, and by providing an automatic control for the belts 5 which operates to stop and start the belts 5 in accordance with the output of the box blank machine. 35

As the wire-connected box blanks leave the box blank machine 4 they pass beneath a clutch control arm 6 carrying a large roller 6a which rides upon the wire-connected box parts. The box parts then ride up on the guides 4 into the 40 bight-forming machine through the action of the belts 5 which frictionally engage the sides of the wired box parts.

As best shown in Fig. 7, belts 5 are rotated about pulleys 7 and 7a. Pulleys 7 are keyed to 45 shafts 9 journaled in frames 8, and pulleys 7a are rotatably mounted on shafts 9a secured to frames 8. Shafts 9 are rotated in a manner presently to be described.

Frames 8 are adjustably secured to the table T 50 and may be adjusted sidewise on table T to accommodate box parts of various widths.

Still referring to Fig. 7, the belts 5 are held against the sides of the box parts by rollers 10 and 10a. Rollers 10 are mounted in castings 11 55 secured to frame 8. Rollers 10a are held against belts 5 by springs 12 interposed between castings 11a and the belts 5. Castings 11a are adjustably mounted on frames 8 to regulate the spring tension against the belts 5.

The belts 5 may be recessed about rollers 13 to provide clearance for the wire-serving and bight-forming devices 14 when box blanks of the type shown in Figs. 1 and 2 are being operated upon. When, however, box ends of the type shown in Fig. 3 are being operated upon the belts 5 need not be recessed and may be run straight as shown in dotted lines in Fig. 7.

As the wired box parts pass through the bight-forming machine they are supported by stock 70 supports 15 adjustably secured to the table T and are held from vertical movement by presser bars 16 which are carried by rods 17.

As shown in Figs. 6 and 8, the belts 5 are driven by a motor 43 which is continuous in op- 75

eration. A pulley 42 secured to the drive shaft of motor 43 is connected by a belt 41 with a pulley 39 which is mounted on a shaft 40. Pulley 39 is driven continuously by motor 43, but because belts 5 must be driven intermittently, pulley 39 is clutched to shaft 40 by a clutch 18 only at those selected times when the belts 5 are to be driven.

The rotation of pulley 39 when clutched to shaft 40 rotates shafts 9 and pulleys 7 through the action of gears 60 on shaft 40 which mesh with gears 61 on shafts 9. Pulleys 7 are keyed to shafts 9 in keyways 59 which extend lengthwise shafts 9 so that pulleys 7 may fall and rise with the table T.

As best shown in Fig. 9, shaft 40 is mounted in brackets 36 secured to frame 37. Gears 60 and 61 are held in mesh by a bracket 62.

The feed belts 5 are started and stopped in the following manner:

When the wired box parts generally designated E in Figs. 1 and 2 sag between the box blank machine and the bight-forming machine and permit control arm 6 to move to the low position shown in dotted lines in Fig. 5, clutch 18 will be operated as hereinafter described to clutch pulley 39 to shaft 40 to cause rotation of pulleys 7 to drive the belts 5. Since the belts 5 move faster than conveyor chains 3 of the box blank machine, they will soon remove the sag in the box parts between the two machines and raise the box parts and the control arm 6 to the position shown in full lines in Fig. 5. This movement of the control arm 6 to the full line position in Fig. 5 disengages clutch 18 in the manner hereinafter described and stops movement of the belts 5.

As shown in Fig. 8, the raising of clutch control arm 6 rocks in a counter-clockwise direction a shaft 19 journaled in brackets 36 secured to machine frame 37. Secured to shaft 19 is a crank 20 pivotally connected to a link 21. The other end of link 21 (see Figs. 10 and 11) has a pin and slot connection with a crank 22 pivoted at 23 in a casting 74. The other end of the crank 22 engages a clutch collar 24 which engages and disengages clutch 18.

The raising of control arm 6 moves link 21 to the left in Fig. 8 and through crank 22 moves clutch collar 24 to release position.

A spring 13 connecting clutch collar 24 with casting 74 holds the clutch collar free of the clutch face when the clutch is engaged and also holds crank 22 in position to be operated by link 21.

After the clutch 18 has been disengaged by the raising of control arm 6, belts 5 remain stationary until the wire-connected box parts between the two machines sag to the position shown in dotted lines in Fig. 5, whereupon clutch 18 will again be engaged through the action of link 21 and crank 22 to cause the belts 5 to start a feeding movement.

Preferably, there is sufficient free movement of clutch collar 24 to permit considerable movement of link 21 before the clutch is released or engaged so that the clutch will not be released until control arm 6 reaches the raised position shown in full lines in Fig. 5, and conversely the clutch will not be engaged until control arm 6 reaches the lowered position shown in dotted lines in Fig. 5.

Thus it will be seen that movement of the belts 5 is automatically started and stopped through the operation of control arm 6 in accordance with the output of the box blank ma-

chine and so that the bight-forming machine will handle the output of the box blank machine without interrupting the operation of the latter.

Because movement of the box parts through the bight-forming machine must be interrupted for each bight-forming operation, a second automatic control for the feed belts 5 is provided to interrupt the feed of the belts 5 when each box part is in correct position to be operated upon by the bight-forming mechanism.

As shown in Fig. 8, the forward edge of each wired box part comes in contact with a stop link 32 having a downwardly projecting nose 33. Stop link 32 is pivotally mounted on a crank 34 secured to a rock shaft 35 mounted in the brackets 36 secured to the frame 37. The movement of the box part against nose 33 of the link 32 moves the link to the left in Fig. 8, thus rocking shaft 35 in a clockwise direction.

As shown in Fig. 7, shaft 35 carries at its right hand end a crank 38 connected to a link 31 the other end of which has a pin and slot connection with crank 22 which operates clutch collar 24. Thus when the forward edge of each box part contacts the nose 33 of link 32 and rocks shaft 35, clutch 18 will be disengaged and the feed of belts 5 will stop. The arrangement is such that the belts 5 are stopped when the forward edge of the box part is in correct position to be operated upon.

The rocking of shaft 35 to discontinue the feed of belts 5 also throws into operation the bight-forming mechanism for one cycle of operation as now explained.

The bight-forming mechanism is operated from a main shaft 54 journaled in frames 37. The shaft 54 is rotated in a counterclockwise direction in Figs. 8 and 9 and in a clockwise direction in Fig. 11. It is operated from a motor 82 through a clutch 53 which connects the shaft 83 of the motor to a shaft 79 journaled in side frame 37. Shaft 79 is connected to main shaft 54 through a gear 78 fast on shaft 79, a chain 80 and a gear 81 connected to shaft 54, the chain 80 passing over the gears 78 and 81. When shaft 35 is rocked to stop movement of the feed belts 5 a crank 44 which is secured to shaft 35 engages and moves a fork 45 secured to a vertical shaft 46 and rocks shaft 46. As best shown in Fig. 13, the rocking of shaft 46 releases a catch 47 and permits a loaded compression spring 48 to rock a shaft 49 mounted in brackets 49a secured to a base frame 37a.

As shown in Figs. 7 and 10, rotary movement of shaft 49 acting through a link 50a, a bell crank 50b, a link 50c, and a lever 50d, moves the yoke of a clutch collar 56 on vertical shaft 68 to partially engage clutch 53 to connect shaft 79 to motor shaft 83. This same rotary movement of shaft 49 acting through link 50a, bell crank 50b, link 50c, a link 50e, a bell crank 50f, and a link 50g, throws a buffer arm 51 from the position shown in Fig. 8 to the position shown in Fig. 9 to permit a one-cycle cam 52 to be released and to allow shaft 54 to be rotated by chain 80 as shaft 79 is rotated.

Partial engagement of clutch 53 as just explained causes initial rotation of shaft 54 and cam 52. As shaft 54 starts turning, the surface of cam 52 contacts a lobe 55 on buffer arm 51 and moves the buffer 51 to the left as shown in Figs. 9 and 12. This movement is transmitted through link 50g, bell crank 50f, link 50e, and lever 50d to clutch collar 56 which is further shifted to engage completely clutch 53, as shown in Fig. 10.

When clutch 53 is engaged as just explained, the bight-forming mechanism is thrown into operation for one complete cycle to perform the bight-forming operations described in said Patent No. 1,933,031. During a bight-forming operation table T is raised and lowered as described in said patent.

As the table T is lowered a cam 63 which is secured to it contacts crank 22 and keeps it from moving until table T rises. As heretofore stated, crank 22 controls the action of clutch 18 which operates the feed belts 5 and when held in this position by the cam 63 the clutch 18 will be disengaged during a fastener supplying operation. Thus it is assured that the clutch 18 which operates the feed belts 5 will remain disengaged while a fastener supplying operation is taking place.

The lowering of the table T also sets a device which will automatically disengage the clutch 53 when the fastener supplying operation is completed, as now described.

Secured to the table T is a piston 15 and a frame 64 both of which rise and fall with the table T. Mounted on frame 64 to pivot vertically is a cam 65 which is normally held in the position shown in Fig. 8 by a spring 66 and an abutment (not shown) on the frame 64 so that the cam is free to move upward but not downward from the position shown in Fig. 8. As the table T falls the cam 65 is pivoted upward about its pivot point by an arm 67 mounted on an extension of shaft 68 upon which the yoke of clutch collar 56 is mounted. When cam 65 passes below arm 67, it snaps in under the arm 67. It remains in this position until table T starts to rise when the fastener supplying operation has been completed. The cam 65 rises with the table and contacts arm 67. Cam 65 and arm 67 are so formed as to move arm 67 out of the path of travel of the cam and this movement of arm 67 causes shaft 68 to be rocked and thereby shift clutch collar 56 to disengage clutch 53 and stop the operation of the bight-forming mechanism. Cam 65 and arm 67 are so shaped and positioned that disengagement of the clutch 53 will not be completed until the table T is in raised position. This rotation of shaft 68 through the action of the linkage hereinbefore described causes buffer 51 to be returned to initial position and thus prevent overrunning of shaft 54.

The rotation of shaft 68 is transmitted through the linkage hereinbefore described to shaft 49 which it rotates counterclockwise (Figs. 7 and 8). This rotation of shaft 49 reloads compression spring 48 and reengages catch 47, the release for catch 47 having been returned to initial position as now described.

As the table T falls, stock stop 32 is held from falling by an arm 70 extending from a bar 71 which is secured to a cross bar 12 (see Fig. 8). As the box blank E moves downward with table T from the position shown in Fig. 9 to that shown in Fig. 12, stock stop 32 is held above the box blank by the arm 70. The removal of the box blank E from contact with nose 33 of stock stop 32 allows the stock stop 32 to be pulled back to the position shown in Fig. 12 by a spring 69 which has been put in tension by the action of the box blank against the stock stop 32. The release of stock stop 32 allows spring 69 to rock shaft 35 and pull the stock stop 32 to the position shown in Fig. 12. This rotation of shaft 35 causes crank 44, fork 45 and shaft 46 to be returned to initial position, thus returning the release for catch 47 into engaging position.

When the table T rises (Fig. 14) nose 33 of stop 32 rests on the stock E. It is prevented from being inadvertently tripped by a knob 57 which rests against bar 71 and prevents the stop 32 from being moved forward until it drops into a clear space between box blanks.

The stock stop 32 is adjustable in length by means of a screw 58 to accommodate various lengths of fasteners with which boxes are to be equipped. The nose 33 of the stop 32 is narrow so that it will fit between the wire C and the belts 5 without interference.

The operation of the machine is as follows:

The box parts E are placed on the continuously moving conveyors 3 of the box blank machine 1. They are fed through the box blank machine which staples the binding wires to the box parts. The wired box parts on leaving the blank machine pass beneath clutch control arm 6 and onto guides 4 into the fastener supplying machine 2. The box parts are drawn from the blank machine and into and through the fastener supplying machine by the moving belts 5. Belts 5 are thrown into operation when clutch control arm 6 reaches the lowered position, i. e., when there is an accumulation of box parts between the machines 1 and 2. Since the belts 5 move faster than conveyors 3 the belts take up these accumulated box parts and draw the wires taut, thus raising clutch control arm 6. When the arm 6 is raised to the position shown in full lines in Fig. 5, clutch 18 is disengaged and feed belts 5 are thrown out of operation. When more box parts have been accumulated between the machines 1 and 2 the control arm 6 falls and reengages the clutch 18 to throw the feed belts 5 into operation.

The movement of the belts 5 will be stopped as each box part trips stock stop 32. This tripping action causes clutch 18 to be disengaged when the box part is in position to be operated upon. This action also trips the latch 47 which starts the fastener supplying mechanism. When a fastener supplying operation is completed its operation is automatically stopped through the action of the one-cycle clutch.

The clutch 18 which controls the operation of the belts 5 is kept disengaged by the action of cam surface 63 against arm 22 during a fastener supplying operation.

When the fastener supplying operation is completed clutch 18 is again engaged through the action of control arm 6 to cause feed belts 5 to move the completed box parts out of the fastener supplying machine and to move additional box parts into the machine to be operated upon.

Among other advantages this invention provides a high speed mass production machine for wiring box parts and providing them with interengageable fastening means. An attendant places the box parts on the conveyors 3 of the blank machine and the completed product is delivered by the feed belts 5 of the fastener supplying machine, the box parts in their movement into and through the fastener supplying machine automatically controlling its operation.

The words "continuous" and "continuously" as used in the claims to define the feed movement of the box parts to the binding wire applying mechanism are intended to define a feed movement in which the box parts are moving at the time the binding wire applying mechanism is operating thereon as distinguished from a feed movement in which the box parts are moved intermittently between operations of the binding

wire applying mechanism and are at rest when said mechanism is operating thereon.

It will be understood that the invention is not to be limited to the specific embodiment shown for purposes of illustration as it may be variously embodied without departing from the invention.

It will also be understood that all of the features of the invention need not be used conjointly as they may be used to advantage in various combinations and subcombinations as defined by the sub-joined claims.

I claim:

1. A machine for equipping box parts with fastening means comprising instrumentalities operable upon a flexible binder secured to a box part to bend the binder to form thereon a loop or bight adapted to connect the box part with another box part, means to feed the box part to said instrumentalities, and means to interrupt the feed of the box part during an operation of said instrumentalities.

2. A machine for equipping box parts with fastening means comprising instrumentalities operable upon a flexible binder secured to a box part to form thereon a fastener adapted to connect the box part with another box part, means to feed the box part to said instrumentalities, and means controlled by the box part to interrupt the feed of the box part during an operation of said instrumentalities.

3. A machine for equipping box parts with fastening means comprising instrumentalities operable upon a flexible binder secured to a box part to bend the binder to form thereon a loop or bight adapted to connect the box part with another box part, means to feed the box part to said instrumentalities, and means to interrupt the feed of the box part and throw said instrumentalities into operation.

4. A machine for equipping box parts with fastening means comprising instrumentalities operable upon a flexible binder secured to a box part to bend the binder to form thereon a loop or bight adapted to connect the box part with another box part, means to feed the box part to said instrumentalities, means to discontinue the feed of the box part during an operation of said instrumentalities, and means to continue the feed of the box part after an operation of said instrumentalities.

5. A machine for equipping box parts with fastening means comprising instrumentalities operable upon a flexible binder secured to a box part to form thereon a fastener adapted to connect the box part with another box part, means to feed the box part to said instrumentalities, means controlled by the box part to discontinue the feed of the box part during an operation of said instrumentalities, and means to continue the feed of the box part after an operation of said instrumentalities.

6. A machine for equipping box parts with fastening means comprising instrumentalities operable upon a flexible binder secured to a box part to form thereon a fastener adapted to connect the box part with another box part, means to feed the box part intermittently to said instrumentalities, means to control said intermittent feed, and means controlled by the box part to discontinue the feed of the box part during an operation of said instrumentalities.

7. A machine for equipping box parts with fastening means comprising instrumentalities operable upon a wire secured to a box part to bend

the binder to form thereon a loop or bight adapted to connect the box part with another box part, means to feed the box part to said instrumentalities, and means automatically to discontinue the feed of the box part during an operation of said instrumentalities.

8. A machine for making box parts comprising mechanism to secure a flexible binder to a box part, means to feed the box part continuously to said mechanism, instrumentalities operable upon the flexible binder to form thereon a fastener adapted to connect the box part with another box part, and means to feed the box part intermittently to said instrumentalities.

9. A machine for making box parts comprising mechanism to secure a flexible binder to a box part, means to feed the box part continuously to said mechanism, instrumentalities operable upon the flexible binder to form thereon a fastener adapted to connect the box part with another box part, means to feed the box part intermittently to said instrumentalities, and means to control said intermittent feed.

10. A machine for making box parts comprising mechanism to secure a flexible binder to a box part, means to feed the box part continuously to said mechanism, instrumentalities operable upon the flexible binder to form thereon a fastener adapted to connect the box part with another box part, means to feed the box part intermittently to said instrumentalities, and means to control said intermittent feed in accordance with the output of said continuous feed.

11. A machine for making box parts comprising mechanism to secure a flexible binder to a box part, means to feed the box part to said mechanism, instrumentalities operable upon the flexible binder to bend the binder to form thereon a loop or bight adapted to connect the box part with another box part, means to feed the box part to said instrumentalities, and means to interrupt the feed of the box part to said instrumentalities during an operation of said instrumentalities.

12. A machine for making box parts comprising mechanism to secure a flexible binder to a box part, means to feed the box part to said mechanism, instrumentalities operable upon the flexible binder to form thereon a fastener adapted to connect the box part with another box part, means to feed the box part to said instrumentalities, and means controlled by the box part to interrupt the feed of the box part to said instrumentalities.

13. A machine for making box parts comprising mechanism to secure a flexible binder to a box part, means to feed the box part to said mechanism, instrumentalities operable upon the flexible binder to bend the binder to form thereon a loop or bight adapted to connect the box part with another box part, means to feed the box part to said instrumentalities, and means to interrupt the feed of the box part to said instrumentalities and to throw said instrumentalities into operation.

14. A machine for making box parts comprising mechanism to secure a flexible binder to a succession of box parts, means to feed the box parts to said mechanism, instrumentalities operable upon the flexible binder to sever the binder between box parts and form on each severed end a fastener adapted to connect one box part to another box part, means to feed the box part to said instrumentalities, and means to interrupt the feed of the box parts to said instrumentalities.

- without interrupting the feed of the box parts to said mechanism.
15. A machine for making box parts comprising mechanism to secure a flexible binder to a succession of box parts, means to feed the box parts continuously to said mechanism, instrumentalities operable upon the flexible binder to sever the binder between box parts and form on each severed end a fastener adapted to connect one box part to another box part, and means to feed the box parts intermittently to said instrumentalities.
16. A machine for making box parts comprising mechanism to secure a flexible binder to a succession of box parts, means to feed the box parts continuously to said mechanism, instrumentalities operable upon the flexible binder to sever the binder between box parts and form on each severed end a fastener adapted to connect one box part to another box part, and means to feed the box parts intermittently to said instrumentalities, and means to control said intermittent feed.
17. A machine for making box parts comprising mechanism to secure a flexible binder to a succession of box parts, means to feed the box parts continuously to said mechanism, instrumentalities operable upon the flexible binder to sever the binder between box parts and form on each severed end a fastener adapted to connect one box part to another box part, means to feed the box parts intermittently to said instrumentalities, and means to control said intermittent feed in according with the output of said continuous feed.
18. A machine for equipping box parts with fastening means comprising instrumentalities operable upon a flexible binder secured to and connecting two box parts to sever the binder between the box parts and bend the binder to form on each severed end a loop or bight adapted to connect one box part to another box part, means to feed the box parts to said instrumentalities, and means to interrupt the feed of the box part during an operation of said instrumentalities.
19. A machine for equipping box parts with fastening means comprising instrumentalities operable upon a flexible binder secured to and connecting two box parts to sever the binder between the box parts and form on each severed end a fastener adapted to connect one box part to another box part, means to feed the box parts to said instrumentalities, and means controlled by the box parts to interrupt the feed of the box parts.
20. A machine for equipping box parts with fastening means comprising instrumentalities operable upon a flexible binder secured to and connecting two box parts to sever the binder between the box parts and bend the binder to form on each severed end a loop or bight adapted to connect one box part to another box part, means to feed the box parts to said instrumentalities, and means to interrupt the feed of the box parts and throw said instrumentalities into operation.
21. A machine for equipping box parts with fastening means comprising instrumentalities operable upon a flexible binder secured to and connecting two box parts to sever the binder between the box parts and form on each severed end a fastener adapted to connect one box part to another box part, means to feed the box parts to said instrumentalities, means to discontinue the feed of the box parts during an operation of said instrumentalities, and means to continue the feed of the box parts after an operation of said instrumentalities.
22. A machine for making box parts comprising mechanism operable upon a moving box part to secure a flexible binder thereto, means to feed the box part to said mechanism, instrumentalities operable upon the flexible binder to form thereon a fastener adapted to connect the box part with another box part, and means to interrupt the feed of the box part to said instrumentalities during an operation of said instrumentalities without interrupting the feed of the box part to said mechanism.
23. A machine for making box parts comprising mechanism operable upon moving box parts to secure a flexible binder thereto, means to feed the box parts to said mechanism, instrumentalities operable upon the flexible binder to sever the binder between box parts and form on each severed end a fastener adapted to connect one box part to another box part, means to feed the box parts to said instrumentalities, and means to interrupt the feed of the box parts to said instrumentalities during an operation of said instrumentalities without interrupting the feed of the box parts to said mechanism.
24. A machine for equipping box parts with fastening means comprising instrumentalities operable upon a flexible binder secured to a box part to form substantially a U-shaped bight thereon and drive the end of the binder into the box part to perpetuate the bight, means to feed the box part to said instrumentalities, and means automatically to interrupt the feed of the box part during an operation of said instrumentalities.
25. A machine for equipping box parts with fastening means comprising instrumentalities operable upon a flexible binder secured to a box part to form thereon substantially a U-shaped bight and to drive the end of the binder into the box part to perpetuate the bight, means to feed the box part to said instrumentalities, and means automatically controlled by the box part to interrupt the feed of the box part during an operation of said instrumentalities.
26. A machine for equipping box parts with fastening means comprising instrumentalities operable upon a flexible binder secured to a box part to form thereon substantially a U-shaped bight and to drive the end of the binder into the box part to perpetuate the bight, means to feed the box part to said instrumentalities, and means automatically to interrupt the feed of the box part and throw said instrumentalities into operation.
27. A machine for equipping box parts with fastening means comprising instrumentalities operable upon a flexible binder secured to the box part to form thereon substantially a U-shaped bight and to drive the end of the binder into the box part to perpetuate the bight, means to feed the box part to said instrumentalities, means automatically to discontinue the feed of the box part during an operation of said instrumentalities, and means automatically to continue the feed of the box part after an operation of said instrumentalities.
28. A machine for equipping box parts with fastening means comprising instrumentalities operable upon a flexible binder secured to a box part to form thereon substantially a U-shaped bight and to drive the end of the binder into the box part to perpetuate the bight, means to feed the box part to said instrumentalities, means automatically controlled by the box part to discon-

- tinue the feed of the box part during an operation of said instrumentalities, and means automatically to continue the feed of the box part after an operation of said instrumentalities.
- 5 29. A machine for making box parts comprising mechanism to secure a flexible binder to a box part, means to feed the box part continuously to said mechanism, instrumentalities operable upon the flexible binder to form thereon substantially a U-shaped bight and to drive the end of the binder into the box part to perpetuate the bight, means to feed the box part intermittently to said instrumentalities, and means automatically to control said intermittent feed. 5
- 10 30. A machine for making box parts comprising mechanism to secure a flexible binder to a box part, means to feed the box part to said mechanism, instrumentalities operable upon the flexible binder to form thereon substantially a U-shaped bight and to drive the end of the binder into the box part to perpetuate the bight, means to feed the box part to said instrumentalities, and means automatically to interrupt the feed of the box part to said instrumentalities during an operation of said instrumentalities. 10
- 15 31. A machine for making box parts comprising mechanism to secure a flexible binder to a box part, means to feed the box part to said mechanism, instrumentalities operable upon the flexible binder to form thereon substantially a U-shaped bight and to drive the end of the binder into the box part to perpetuate the bight, means to feed the box part to said instrumentalities, and means automatically to interrupt the feed of the box part to said instrumentalities and to throw said instrumentalities into operation. 15
- 20 32. A machine for equipping box parts with fastening means comprising instrumentalities operable upon a flexible binder secured to and connecting two box parts to sever the binder between the box parts and form on each severed end substantially a U-shaped fastener adapted to connect one box part to another box part, means to feed the box parts to said instrumentalities, and means automatically to interrupt the feed of the box parts and throw said instrumentalities into operation. 20
- 25 33. A machine for making box parts comprising mechanism operable upon a moving box part to secure a flexible binder thereto, means to feed the box part to said mechanism, instrumentalities operable upon the flexible binder to form thereon substantially a U-shaped fastener, and means 25
- 30 automatically to interrupt the feed of the box part to said instrumentalities during an operation of said instrumentalities without interrupting the feed of the box part to said mechanism. 30
- 35 34. A machine for squipping box parts with fastening means comprising instrumentalities operable upon a metallic binder secured to a box part to form a bight thereon and drive the end of the binder into the box part to perpetuate the bight, means to feed the box part to said instrumentalities, and means to interrupt the feed of the box part during the operation of said instrumentalities. 35
- 40 35. A machine for equipping box parts with fastening means comprising instrumentalities operable upon a metallic binder secured to a box part to form a bight thereon and drive the end of the binder into the box part to perpetuate the bight, means to feed the box part to said instrumentalities, and means automatically to interrupt the feed of the box part during an operation of said instrumentalities. 40
- 45 36. A machine for equipping box parts with fastening means comprising instrumentalities operable upon a metallic binder secured to a box part to form a bight thereon and drive the end of the binder into the box part to perpetuate the bight, means to feed the box part to said instrumentalities, and means to interrupt the feed of the box part during the operation of said instrumentalities and to throw said instrumentalities into operation. 45
- 50 37. A machine for making box parts comprising mechanism to secure a flexible binder to a box part, means to feed the box part to said mechanism, instrumentalities operable upon the flexible binder to form a bight thereon and to drive the end of the binder into the box part to perpetuate the bight, means to feed the box part to said instrumentalities, and means automatically to interrupt the feed of the box part to said instrumentalities during an operation of said instrumentalities. 50
38. A machine for equipping box parts with fastening means comprising instrumentalities operable upon a flexible binder secured to and connecting two box parts to sever the binder between the box parts and form a bight on each severed end, means to feed the box parts to said instrumentalities, and means automatically to interrupt the feed of the box parts during an operation of said instrumentalities. 50

ALFRED L. ROSEN MUND.
